AZO DYE

Francis H. Smith, Woodstown, N. J., assignor to
E. I. du Pont de Nemours & Company, Wil-
mington, Del., a corporation of Delaware

No Drawing. Application March 26, 1940,
Serial No. 326,005

2 Claims. (Cl. 8—24)

This invention relates to dyeing and to new dyestuff compositions. In the dyeing of so-called union goods, which consist in general of cloth containing mixed fibers with different dyeing properties, where colored effects are desired, a useful process involves the dyeing of one of the fibers with a dye which is not substantive to the other fiber and thereafter dyeing the second fiber with a dye which is not substantive to the first. This process is imperfect, however, particularly as applied to azo dyes in that some azo dyes, which are substantive to cotton, and are substantially non-substantive to cellulose acetate, stain the cellulose acetate fibers sufficiently to produce imperfect results. For example, if a cloth is composed of a mixture of cotton and cellulose acetate threads, it may be desired to dye the cotton brown and the cellulose acetate scarlet. However, if the brown stains the cellulose acetate, the scarlet produced will be muddy and the effect imperfect. The trade has developed this process of dyeing to the point where a large number of colors are known which are highly substantive to one or the other of the fibers but have little affinity for the other. Nevertheless, this imperfection still remains.

It is an object of this invention to improve colors having high affinity for one of these fibers and low affinity for the other. A more specific object of the invention is to improve the dyeing properties for this purpose of those colors which are substantive to cotton but which stain cellulose acetate.

It has been proposed to use highly porous solid adsorbents, such as activated carbon, to decrease the acetate silk staining impurities of azo dyestuffs which are used in the indicated process. Heretofore, the activated carbon had been added to the dyestuff solution, allowed to remain there long enough to decrease the acetate staining impurities of the dye, and removed therefrom by filtration prior to the isolation of the dye. In the prior art the activated carbon was always added to, and removed from, the dye bath by processes involving filtration, clarification and sometimes reworking.

The objects of this invention are accomplished, generally speaking, by preparing the dye, mixing activated carbon therewith and isolating the dye and the carbon without separating them. We have found that direct and developed dyestuffs can be considerably improved with regard to cellulose acetate staining qualities by this process.

The following examples, which are not intended as a limitation, illustrate the invention.

Example I

Approximately 10 grams of Color Index No. 581 was milled with 0.6 gram of activated carbon for

approximately 16 hours. A piece of cloth was dyed with the composition. A piece of the same cloth was dyed with the same strength of the same dye not containing activated carbon. The dyeing effect on the cotton threads of the cloth was not less but the dyeing effect of the dyestuff on the cellulose acetate was markedly less in the case of the color containing the carbon.

The experiment was repeated in connection with the following colors using a variety of concentrations both of carbon and of dyestuff. Results uniformly showed a decrease in the acetate staining properties of the colors.

TABLE I

Example	Product
II	Color Index No. 581.
III	Color Index No. 582.
IV	Color Index No. 267.
V	Color Index No. 583.
VI	Color Index No. 584.
VII	Color Index No. 502.
VIII	Color Index No. 512.
IX	Color Index No. 484.
X	Color Index No. 387.
XI	Color Index No. 561.
XII	Color Index No. 561.
XIII	H acid $\xrightarrow{\text{Cleves}}$ (para-phenylene-diamine); $\xrightarrow{\text{Cleves}}$ (meta-phenylene-diamine).
XIV	Amino-G acid $\xrightarrow{\text{Cleves}}$ meta-toluidine $\xrightarrow{\text{Cleves}}$ 1,6-Cleves $\xrightarrow{\text{Cleves}}$ meta-toluidine-para-amino-benzoyl (developed with beta-naphthol).
XV	Phenol $\xrightarrow{\text{benzidine}}$ benzidine $\xrightarrow{\text{H acid}}$ H acid $\xrightarrow{\text{benzidine}}$ meta-phenylene-diamine $\xrightarrow{\text{H acid}}$ gamma acid.
XVI	Amino-G acid $\xrightarrow{\text{Cleves}}$ meta-toluidine $\xrightarrow{\text{Cleves}}$ meta-toluidine para-amino-benzoyl-benzoylated.
XVII	Cleves $\xrightarrow{\text{benzidine}}$ para-phenylene-diamine $\xrightarrow{\text{H acid}}$ S acid $\xrightarrow{\text{benzidine}}$ para-phenylene-diamine.
XVIII	Para-chloro-aniline $\xrightarrow{\text{benzidine}}$ H acid $\xrightarrow{\text{benzidine}}$ benzidine $\xrightarrow{\text{H acid}}$ mixed Cleves acid.
XIX	1,6-Cleves acid $\xrightarrow{\text{benzidine}}$ H acid $\xrightarrow{\text{benzidine}}$ benzidine $\xrightarrow{\text{H acid}}$ mixed Cleves acid.
XX	Aniline $\xrightarrow{\text{benzidine}}$ H acid $\xrightarrow{\text{benzidine}}$ benzidine $\xrightarrow{\text{H acid}}$ alk.
XXI	Para-chloro-aniline $\xrightarrow{\text{benzidine}}$ H acid $\xrightarrow{\text{benzidine}}$ benzidine $\xrightarrow{\text{H acid}}$ alk.
XXII	Para-nitro-aniline $\xrightarrow{\text{benzidine}}$ H acid $\xrightarrow{\text{benzidine}}$ benzidine $\xrightarrow{\text{H acid}}$ meta-phenylene-diamine.
XXIII	Ortho-chloro-para-nitro-aniline $\xrightarrow{\text{benzidine}}$ H acid $\xrightarrow{\text{benzidine}}$ benzidine $\xrightarrow{\text{H acid}}$ meta-phenylene-diamine.
XXIV	Aniline $\xrightarrow{\text{benzidine}}$ H acid $\xrightarrow{\text{benzidine}}$ benzidine $\xrightarrow{\text{H acid}}$ alpha-naphthylamine.
XXV	(Ortho - amino - phenol - para - sulfonic acid $\xrightarrow{\text{resorcinol; coppered}}$ benzidine $\xrightarrow{\text{benzidine}}$ salicylic acid).
XXVI	Dioxy-S acid $\xrightarrow{\text{benzidine}}$ toluidine $\xrightarrow{\text{benzidine}}$ gamma acid $\xrightarrow{\text{benzidine}}$ dioxy-S acid.
XXVII	Naphthionic acid $\xrightarrow{\text{benzidine}}$ 2R acid $\xrightarrow{\text{benzidine}}$ meta-phenylene-diamine $\xrightarrow{\text{benzidine}}$ salicylic acid.
XXVIII	Dehydrothiophene - para - tolylene - sulfonic acid $\xrightarrow{\text{benzidine}}$ resorcinol $\xrightarrow{\text{benzidine}}$ aniline.
XXIX	Acetylaminocleves $\xrightarrow{\text{benzidine}}$ mets-toluidine $\xrightarrow{\text{benzidine}}$ salicylic acid.
XXX	Salicylic acid $\xrightarrow{\text{benzidine}}$ benzidine $\xrightarrow{\text{benzidine}}$ resorcin $\xrightarrow{\text{benzidine}}$ naphthionic acid.
XXXI	Naphthionic acid $\xrightarrow{\text{benzidine}}$ meta-toluylene-diamine $\xrightarrow{\text{benzidine}}$ meta-toluylene-diamine.
XXXII	Amino-salicylic acid $\xrightarrow{\text{benzidine}}$ alpha-naphthylamine $\xrightarrow{\text{benzidine}}$ gamma acid.
XXXIII	Meta-toluylene-diamine $\xrightarrow{\text{benzidine}}$ gamma acid $\xrightarrow{\text{benzidine}}$ para-phenylene-diamine $\xrightarrow{\text{benzidine}}$ Cleves acid.
XXXIV	Cresidine $\xrightarrow{\text{benzidine}}$ amino-Cleves acid $\xrightarrow{\text{benzidine}}$ 1,7-Cleves acid $\xrightarrow{\text{benzidine}}$ 1,4-hydroxy acid (developed with beta-naphthol).

Example XXXV

A 0.1 gram mole charge of Color Index No. 581 was prepared in the customary manner. After the final coupling to meta-phenylene-diamine was complete, 2.0 grams of activated carbon was added. The suspension was heated with stirring to 80-85° C. for approximately 20 minutes. The suspension was salted with sodium chloride to a clear rim, filtered and dried. The product stained cotton as well or better and cellulose acetate noticeably less than a product prepared in a similar manner except omitting the addition of activated carbon.

Example XXXVI

Benzidine sulfate paste equivalent to 9.2 parts of pure benzidine was tetrazotized in the usual manner and coupled in strong mineral acidity with H acid paste equivalent to 16.25 parts of pure mono-sodium salt of 1-amino-8-naphthol-3,6-disulfonic acid. After stirring overnight at room temperature, the temperature was lowered to 10° C., the acidity was reduced with an aqueous solution of 5.25 parts of soda ash, and 1 part of activated carbon was added. Benzene diazonium chloride solution, made in the customary manner from 5.36 parts of aniline, was added, and then an aqueous solution of 12.9 parts of soda ash and 1 part of activated carbon were added immediately. After one-half hour, the temperature was 19° C. One part of activated carbon was added. Then 0.813 part of meta-phenylene-diamine was added in the form of an aqueous solution. The mixture was allowed to stir ten minutes before the addition of 1 part of activated carbon. Five minutes later 4.83 parts of meta-phenylene-diamine in the form of an aqueous solution was added. One part of activated carbon was added immediately thereafter. The reaction mixture was allowed to stir for one hour, and then 1 part of activated carbon was added. The dyestuff was salted, isolated, and dried in the customary manner. The trisazo dyestuff thus synthesized was a direct black which stained acetate silk con-

siderably less than the identical dye lacking the activated carbon.

The usual commercially available types of activated carbon are useful; for example: Norite A, Nuchar, Colloidal Black Dispersion B, Colloidal Black Dispersion O, Colloidal Black Dispersion M, Darco G-60, and Aquoid 45-R-X. No definite amount of these products was required, varying amounts being satisfactory in every case.

10 The activated carbon may be added at any convenient stage during the process of preparation of the dyestuff, but is not to be removed from the dyestuff.

15 The herein-described invention has a distinct advantage over known methods of improving the cellulose acetate staining properties of direct and developed colors. No additional filtrations, clarifications and reworking procedures are necessary to obtain the desired effect, as is the case with 20 methods disclosed in the prior art.

25 As many apparently widely different embodiments of this invention may be made without departing from the spirit and scope thereof, it is to be understood that I do not limit myself to the 28 specific embodiments thereof except as defined in the appended claims.

I claim:

30 1. The process of dyeing union textiles containing cellulose acetate fibers without imparting substantial stain to the acetate, and with the production of color having good discharge properties, which comprises applying a composition containing a direct cotton azo dye, activated carbon, and water to the said textiles.

35 2. The process of dyeing union textiles containing cellulose acetate fibers without imparting substantial stain to the acetate, and with the production of color having good discharge properties, which comprises applying a composition containing the compound represented by the formula: 40 aniline→H-acid→benzidine→meta-phenylene-diamine, activated carbon, and water to the said textiles.

FRANCIS H. SMITH.
